ROD BENDING APPARATUS

Patrick J. Cotter, Long Island City, and Marcy
D'Onofrio, Richmond Hill, N. Y.

Application February 15, 1939, Serial No. 256,442

3 Claims. (CL 153—11)

This invention relates to improvements in rod bending apparatus and more specifically to apparatus for manually bending rods for use in the reinforcement of concrete structures.

5 In reinforced concrete construction, it is the practice to support reinforcing rods upon the I beams, and to form "drops" in the length of the rod to be disposed between adjacent beams. It has been the general practice in the past to manually bend the rod by guesswork and which requires the services of a number of operators in the bending of a single rod. It is therefore the main purpose of this invention to provide an apparatus, by the use of which, a rod may be accurately bent by a single operator.

Another important feature of the invention resides in rod bending apparatus which may be set up for use on the premises of the concrete structure to be erected to bend the reinforcing rods to meet the structural specifications of the particular job as the construction operations progress.

Another feature of the invention is to provide a rod bending apparatus wherein the bends imparted to a reinforcing rod are uniform to assure the forming of the "drops" of uniform depths throughout the length of the rod.

A further feature of the invention is the provision of a rod bending apparatus which may be set to form different length bends in a reinforcing rod, whereby to vary the depth of the "drop" to meet the specifications called for on a particular job.

A still further feature of the invention is the provision of a reinforcing rod bending apparatus which is simple and inexpensive of construction, which requires a minimum amount of effort on the part of an operator to effect a bending of a rod; and which greatly speeds up the bending of the rods over past methods, thus saving time and labor costs.

With these and other objects in view, the invention resides in the novel construction, combination and arrangement of parts, the essential features of which are hereinafter fully described in the following specification, are particularly pointed out in the appended claims, and are illustrated in the accompanying drawings, in which:

Figure 1 is a top plan view broken away intermediate its ends, and illustrating the manner in which a hook is bent at one end of a reinforcing rod.

Figure 2 is a fragmentary top plan view illustrating the manner in which the first angular bend is formed in a reinforcing rod.

Figure 3 is a fragmentary top plan view with the angular stop member placed in position with the first angular bend of the rod in abutting engagement therewith.

Figure 4 is a perspective view illustrating the final bend in the forming of the second "drop" in a reinforcing rod.

Figure 5 is a side elevational view of the preferred embodiment of the rod bending tool.

Figure 6 is an enlarged vertical transverse sectional view on the line 6—6 of Figure 4.

Figure 7 is a perspective view of an adjustable bending tool which may be used in connection with the apparatus, the adjustable jaw being illustrated in separated position in full lines and in operative position in dot and dash lines.

Figure 8 is a fragmentary vertical longitudinal sectional view through the head of the tool shown in Figure 7.

Figure 9 is a perspective view of a modified form of bending tool.

Figure 10 is a cross sectional view through several I beams showing a bent reinforcing rod supported thereby.

Figure 11 is a fragmentary top plan view showing the use of the auxiliary rail for forming a shallow "drop" in a rod.

Referring to the drawings by reference characters, the numeral 10 designates a flat table or work bench made of wood and which may be of any width within the limit of the maximum depth of the "drop" to be formed in the bending of a steel reinforcing rod to be used on a particular reinforced concrete construction job. The table 10 is of a length approximating the length of the rod to be bent so that the rod may be bent at spaced distances throughout its length without disturbing the position of the rod upon the table. The table 10 includes a flat top 11 supported by legs 12 of a length to conveniently position the top 11 relatively to the height of an average operator.

Fixedly supported upon the table top 11 and extending lengthwise inwardly of the front longitudinal edge thereof are a pair of spaced parallel angle rails 13 and 14, which extend from the left end of the table to a point short of the right end thereof. The rail 13 includes a horizontal base flange 15 which fits against the table top 11 and extends in a rearward direction, and an upstanding flange 16. The base flange 15 has spaced openings 17 therealong through which fastening screws 18 pass into the wood top 11. The rail 13 may be termed a fixed rail by reason of its screw fastening elements, whereas the

rail 14 may be termed an adjustable or removable rail by reason of its fastening elements now to be explained.

The rail 14 includes a horizontal base flange 19 which extends toward the front of the table top and an upstanding flange 20. The base flange 19 is provided with spaced openings 21 through which nails 22 pass into the table top 11. By reason of the nail fastening means for the rail 14, it is possible to pry the same up and readjust it in parallel relation to the rail 13 when the depth of the "drop" to be bent into a rod exceeds the original adjusted relation of the rails. However, it is possible to employ auxiliary rail members in conjunction with the two fixed rails 13 and 14 to effect the bending of a shallower "drop" in the rod without disturbing the original maximum adjustment of the rails, as will be hereinafter explained.

20 Fixedly mounted in close spaced relation to the right end of the rail 13 is a relatively short angle rail member 23 which is secured to the table top 11 by screws 24. The space between the adjacent upstanding flanges of the rail 13 and rail member 23 is such as to freely receive the thickness or cross sectional diameter of the rod to be bent.

The rod bending apparatus also includes a bending tool 25 which comprises an elongated handle 26 having an inverted U shaped jaw 27 welded to one end thereof. The jaw 27 is of a length approximating the length of the bend to be formed in a reinforcing rod, and the channel or space between the walls of the jaw is such as 35 to freely receive the cross sectional area of the rod to be bent. The free end of the handle has a tubular socket 28 welded thereto.

In Figure 1 of the drawings, there is illustrated the first step of a reinforcing rod bending operation, wherein a straight reinforcing rod A is placed lengthwise on the table top 11 flat against the inner side of the upstanding flange 16 of the rail 13. The right end of the rod A is shown extended beyond the right end of the rail 13 and rail member 23 to facilitate the bending of an anchor hook on one end of the rod. A row of gauge markers 29 is provided on the table top beyond the outer end of the rail member 23 which are indicative of inches to facilitate the lining up 50 of the end of the rod to measure the length of the bill of the hook to be formed. After lining up the right end of the rod A, the operator inserts the socket 28 of the tool 25 onto the said end of the rod with the jaw end of the tool open 55 side up. The operator manually swings the tool 25 in a rearward direction as shown by the dotted position of the tool in Figure 1. The tool is swung until the bill of the hook B is substantially parallel to the length of the rod, and the 60 rounded bend is formed by the rod being fulcrumed on the right end of the rail 13.

After the hook B has been formed, the rod A is turned forward a half turn to cause the hook B to hookingly engage the rail member 23 as 65 shown in Figure 2 of the drawings. The rod A is now in position to receive the first bend to form a "drop" and arranged along the table top 11 adjacent the inner side of the rail 13 are spaced rows of guide markers 30 which may be 70 in the form of nails driven into the table top 11. The operator now applies the tool 25 to the intermediate portion of the rod A with the open side of the jaw down over the rod. The end of the jaw 27 is lined up with a particular one of 75 the guide markers of the right end group depend-

ing upon the distance at which the first "drop" is to be formed from the hook B. With the jaw 27 fitted over the rod A and the handle 26 extending forwardly, the operator turns the handle from left to right and the swinging movement of the tool is limited by reason of the ends of the jaw abutting the inner sides of the rails 13 and 14 as shown in Figure 2 of the drawings. The length of the jaw 27 is proportionate to the distance between the rails 13 and 14, so that when the tool reaches the limit of its turning movement, the bent portion forms an angular leg C which is approximately disposed at a forty-five degree angle with respect to the straight unbent portions of the rod. After the bending of the first leg of the first "drop" in the rod, the operator removes the tool and places an angle rail stop member 31 upon the table against which the angular leg portion C abuts. The stop member 31 is removably secured by a pair of pins 32 which pass through openings in the base flange of the angle rail stop member and enter any corresponding pair of openings 33 provided in the table top 11. The openings 33 are arranged in two rows to facilitate adjustment of the stop member 31 and when in anchored position, the stop member assumes an angular position corresponding to the angular position of the bent leg portion C so as to flatly engage said leg portion as best seen in Figure 3.

Having formed the first bend in the rod to form the leg portion C of the first drop and positioned the leg portion C against the stop member 31, the operator may now proceed to successively make the other bends at spaced distances throughout the remaining length of the rod. To complete one "drop" the operator applies the tool to the left the required measured distance from the lower bend in the leg portion C, it being noted that the portion of the rod to which the tool is applied is now disposed against the inner side of the front rail 14. Guide markers 34 are arranged in spaced relation on the table top adjacent the inner side of the rail 14 to enable the lining up of the jaw to the tool 25 when making up-bends now to be explained. With the tool 25 properly positioned over the rod with the rod in the jaw 27, and the handle 26 extending forward, the operator manually turns the handle toward the left until the ends of the jaw abut the inner sides of the rails 13 and 14 whereupon the second angular leg portion D of the "drop" is formed and which leg portion D is also disposed at an approximately forty-five degree angle relative to the length of the rod. The leg portions C and D are joined by a bridge portion 55 E, and these portions combined form a "drop" F of a particular width and depth, depending upon the specifications of a particular reinforced concrete construction job. Any number of like "drops" F may be formed at spaced distances 60 along the length of the rod A, but we have only illustrated two in the drawings.

After a rod A has been bent throughout its length to provide the desired number of "drops" F, it is supported by clips G (Figure 10) upon the I beams H of a structural steel framework, the hook end B being hookingly engaged with a reinforcing rod J disposed at right angle to the rod A. The two "drops" F are of uniform depth 65 but in some instances it is desired that the "drops" in a single rod be of different depths. We have therefore provided a means for bending a shallower "drop" without disturbing the original adjusted position of the fixed rails 13 70 75 80 85 90 95 98

and 14 as shown in Figure 11 of the drawings in full lines and in dotted lines in Figure 1.

To shorten the depth of the "drop", auxiliary rail members 35 are placed upon the table top 11 inwardly of and adjacent the rail 14 at locations thereon where the bends are to be formed. The auxiliary rail members are held in position parallel to the rails 13 and 14 by removable pins 36 which enter holes 31 in the table top. The auxiliary rail members 35 coact with the rail 13 instead of the rail 14, and the rail 13 and rail members are abutted by the ends of the jaw 21 of the tool 25, although a tool having a shorter length jaw is used, for it is the length of the jaw which determines the depth of the "drop" and the angle of the bend.

From the foregoing description, it will be understood that after the hook B is formed on one end of the rod A and the rod is turned to cause the hook B to engage the rail member 23, that the rod A is held against accidental shifting movement toward the left when making down-bends in the rod, the stop member 31 with which the first down-bend abuts, acts to prevent accidental shifting of the rod toward the right when making up-bends.

In Figures 7 and 8 of the drawings, we have illustrated an adjustable tool 38 which may be used for bending rods of various cross sectional dimensions. The tool 38 includes a flat head 39 which has a depending fixed jaw 40. The head 39 has an internally screw threaded socket 41 welded thereon which receives the threaded end of a tubular handle 42 made up of a plurality of different diameter pipe sections 42' which gradually diminish in diameter outwardly from the head 38. By separating or connecting the handle sections, the same may be selectively brought into use as a socket for bending the hook on the ends of rods of different cross sectional dimensions.

The head 39 has three spaced elongated slots 43 which respectively receive three guide pins 44 extending upwardly from the horizontal flange 45 of an adjustable angle jaw member 46. The standard cross sectional dimensions of reinforcing rods for concrete construction are standardized as $\frac{3}{4}$ ", $\frac{5}{8}$ ", and $\frac{1}{2}$ ", and we have provided for these three fixed adjustments by arranging two converging rows of unthreaded bolt openings 47 in the head 39, any corresponding two of which may be brought into registration with two related threaded openings of the six threaded openings 48 in the horizontal flange 45. A pair of bolts 49 pass through the pairs of aligned openings 47 and 48 and have threading connection with openings 48 to secure the adjustable jaw member 46 in a fixed position relative to the fixed jaw 40. After adjusting the jaw member 46 to a fixed position to accommodate a particular diameter of rod, the tool 38 is used in the same manner as the tool 25.

In Figure 9, a modified form of tool 50 is illustrated and which includes a flat head 51 welded to one end of a handle 52. A socket 53 is welded to the upper side of the handle at the free end thereof for bending the hook B at one end of the rod. Spaced opposed bending pins 54-54 extend from the underside of the head and serve the same purpose as the channel jaw 27 of the tool 25. One pin 54 engages one side of the rod to be bent and the other pin 54 engages the opposite side, whereby turning of the handle causes a predetermined bend to be formed in the rod.

The space between the pins 54 determines the length of the bend to be formed in a rod.

While we have shown and described what we consider to be the preferred embodiments of our invention, we wish it to be understood that such changes as come within the scope of the appended claims may be resorted to if desired.

Having thus described the invention, what we claim as new and desire to secure by Letters Patent of the United States, is:

1. Apparatus for the bending of reinforcement rods for use in connection with concrete constructions comprising in combination, an elongated table; a pair of spaced parallel rails fixed lengthwise to the table against the inner side of one of which a rod to be bent is adapted to be placed; means on said table adjacent the end of one of said rails adapted to cooperate therewith in holding a rod while one end thereof is being bent, and said means also serving to engage the bent end of a rod for arresting shifting movement of the rod in one direction while making a second bend intermediate the ends thereof; a bending tool having a rod receiving jaw of greater length than the distance between the rails whereby an angular second bend may be made in a rod of a length approximating that of the jaw when a rod is gripped in the jaw and the bending tool is turned until the ends of the jaw abut the rails; and a removable stop member mounted on said table between said rails and extending angularly relative thereto at an angle corresponding to the angle of the second bend formed in a rod and against which the angular second bend is adapted to abut to arrest shifting movement of a rod in the opposite direction so as to hold a rod against lengthwise shifting movement during the formation of subsequent bends in the rod.

2. Apparatus for the bending of reinforcement rods for use in connection with concrete constructions comprising in combination; an elongated table; a pair of spaced parallel rails fixed lengthwise to the table against the inner side of one of which a rod to be bent is adapted to be placed; means on said table adjacent the end of one of said rails adapted to cooperate therewith in holding a rod while one end thereof is being bent, and said means also serving to engage the bent end of a rod for arresting shifting movement of the rod in one direction while making a second bend intermediate the ends thereof; a bending tool including spaced coextensive jaw members providing a jaw receiving channel therebetween, the length of the jaw members being greater than the distance between the rails whereby an angular second bend may be made in a rod of a length approximating that of the jaw members when a rod is gripped in the channel between the jaws and the bending tool is turned until the ends of the jaw members abut the rails; and a removable stop member mounted on said table between said rails and extending angularly thereto at an angle corresponding to the angle of the second bend formed in a rod and against which the angular second bend is adapted to abut to arrest shifting movement of a rod in the opposite direction so as to hold a rod against lengthwise shifting movement during the formation of subsequent bends in the rod.

3. Apparatus for bending of reinforcement rods for use in connection with concrete constructions comprising in combination; an elongated table; a pair of spaced parallel rails fixed lengthwise to the table against the inner side of one of which a rod to be bent is adapted to be placed;

- means on said table adjacent the end of one of said rails adapted to cooperate therewith in holding a rod while one end thereof is being bent, and said means also serving to engage the bent end of a rod for arresting shifting movement of the rod in one direction while making a second bend intermediate the ends thereof; a bending tool having a rod receiving jaw of greater length than the distance between the rails where-
5 by an angular second bend may be made in a rod of a length approximating that of the jaw when a rod is gripped in the jaw and the bending tool is turned until the ends of the jaw abut the rails; an auxiliary rail member of less length than the
10 rails and positioned between the rails in parallel spaced relation thereto adapted to form an abut-
15 ment for a rod being bent in a "drop" that is shallower than the distance between the rails, means on the table coacting with the auxiliary rail member for detachably supporting the auxiliary rail on the table; and a removable stop mem-
ber mounted on said table between said rails and extending angularly relative thereto at an angle corresponding to the angle of the second bend formed in a rod and against which the angular second bend is adapted to abut to arrest 10 shifting movement of a rod in the opposite direction so as to hold a rod against lengthwise shifting movement during the formation of subsequent bends in the rod.
